MATERIAL HANDLING DEVICE

Robert W. Kaltenbach, Cleveland Heights, Ohio

Original application May 13, 1938, Serial No. 207,776. Divided and this application June 22, 1939, Serial No. 280,457

1 Claim. (Cl. 193—17)

This invention relates to material handling devices for transferring material such as coal from railway cars to vessels, and the present application is a division of my copending application Serial No. 207,776 filed May 13, 1938, granted as Patent No. 2,216,742. One form of device that is suitable for this purpose has included a material receiving member such as a chute or pan, and an extensible vertical spout which is mounted for universal swinging movement adjacent the outer end of the pan.

Heretofore the connection between the pan and the supporting girder embodied what might be termed a piano hinge, that is, a hinge embodying registering straps extending along the top end of the pan through which a succession of hinge pins extend. This construction, however, is objectionable because of the forces which tend to buckle or bend the supporting girder and because of the high erection and maintenance costs. One of the important maintenance costs has been that of maintaining proper alignment of the supporting girder.

An object of my invention, therefore, is to make a trunnion connection between the pan and the supporting girder that will obviate the old type of construction and which therefore, will reduce the erection and maintenance costs. Additionally, my invention includes a hinge construction that will transmit the load stresses more directly to the main columns of the frame and thereby simplify the construction and lower the maintenance cost.

Referring now to the drawings, Fig. 1 is a side elevation of a car dumper embodying my invention; Fig. 2 is a top plan view partly in section of part of the car dumper showing the pan construction; Fig. 3 is a section taken on the line 3—3 in Fig. 2 but on a somewhat larger scale; and Fig. 4 is a section taken on the line 4—4 in Fig. 3.

A material handling device with which I have illustrated my invention embodies a car dumper having a frame 10 in which a car supporting cradle 11 is movably mounted; the cradle being shown in full lines in tilted position with a car 12 mounted thereon and clamped thereto. The content of the car is receivable in a pan 13 which may be pivoted to a supporting girder 7 and which is adapted to be swung about the pivot by means of a cable 15. The pan structure includes a framework 16 on which the pan is supported, it being understood that the floor of the pan rests upon the framework and that the framework is pivoted to the girder at 6. The pan

is wider at its top than the length of any car that may be received by the cradle, but the sides of the pan converge toward the outer end thereof at which point a telescopic spout 20 is arranged to receive the contents of the pan. The spout illustrated is telescopic and is pivotally mounted on the pan framework at 21 and is provided with two sets of sheaves indicated at 22 and 23 for receiving the outboard and inboard cables 24 and 25 respectively. In practice, the top of the pan is enclosed from the bottom nearly to the top, so as to hold a substantial quantity of material whenever the lower end of the spout is closed.

15 The mechanism for operating the inboard cables is illustrated in general at 30 and 30—A as comprising electric motor driven drums which are mounted on the framework beneath the pan while the motors for operating the outboard cables are indicated at 31 and 31—A as being mounted on a support that extends across the upper side of the pan. The inboard and outboard cable guiding sheaves are indicated at 35 and 36 respectively and are preferably journaled in 20 bearings which may be shifted with respect to the spout pivot. Thus, in the form shown in Fig. 1, the sheaves 36 are supported on an outrigger 38 that is rigidly attached to the pan framework. The outrigger supports the control house 40 in which suitable controls are provided for operating the telescopic spout actuating motors. While I have illustrated electric motors for actuating the drums, I may, if desired, use steam engines or other motive power.

25 To support the pan for a hinging movement upon the frame and at the same time eliminate the piano hinge type of construction heretofore employed, I use two hinge pins 6 that are positioned at opposite ends of the pan adjacent the 30 inlet end thereof and each of which is journaled in a bearing 92 which is carried in a bracket 94 on the girder 7 and adjacent the column 96. The girder is movable with reference to the column by means of a screw shaft 5 which is adapted 35 to be rotated by any suitable mechanism. In this way, the load stresses are transmitted more directly to the main columns of the frame and hence, the girder is relieved of practically all of the horizontal force tending to bend it. Additionally, by utilizing the trunnion mounting, I have greatly reduced the cost of erection and the cost of maintenance.

40 From the foregoing description, it will be apparent that I have provided a simple and effective mechanism for lessening the bending stresses

that are exerted upon the pan supporting girder of the frame by employing a hinge construction which transmits the load stresses more directly to the columns of the frame. The hinge construction illustrated in Fig. 4 shows a two-point support on the pan and a one-point support on the girder. This assures a sufficiently strong connection that permits the utilization of a relatively short hinge pin.

I claim:

In a car dumper, the combination of a frame,

a girder supported thereby, a material receiving pan mounted for swinging movement upon the girder, the connection between the pan and girder comprising two spaced trunnions, each of which has a two-point support on the pan and a one point support on the girder, and the pan being free of any connection with the girder between the hinge pins.
